UNITED STATES PATENT OFFICE.

ALEXANDER YAREMENKO, OF NEW YORK, N. Y.

DESIGN FOR A COUCH.

Application filed October 13, 1926. Serial No. 19,316. Term of patent 14 years.

To all whom it may concern:

Be it known that I, ALEXANDER YAREMENKO, a citizen of the United States, and residing in the borough of Manhattan, of the city of New York, county of New York, and in the State of New York, have invented a new, original, and ornamental Design for a Couch, of which the following is a specification, reference being had to the accompanying drawings, forming a part thereof.

The figure is a front perspective view of a couch embodying my design.

I claim:

The ornamental design for a couch, as shown.

This specification signed this 29th day of September, A. D. 1926.

ALEXANDER YAREMENKO.
